US00D542828S

(12) **United States Design Patent** (10) Patent No.: **US D542,828 S**
Tsukahara (45) Date of Patent: **** May 15, 2007**

(54) **LCD VIDEO PROJECTOR**

(75) Inventor: **Takashi Tsukahara**, Osaka (JP)
(73) Assignee: **Matsushita Electrical Industrial Co., Ltd.**, Osaka (JP)
(**) Term: **14 Years**
(21) Appl. No.: **29/254,874**
(22) Filed: **Mar. 1, 2006**
(30) **Foreign Application Priority Data**
Dec. 27, 2005 (JP) 2005-038298
(51) **LOC (8) Cl.** **16-02**
(52) **U.S. Cl.** **D16/230; D16/221; D16/225**
(58) **Field of Classification Search** **D16/205, D16/208, 213, 221, 225, 230, 231, 234; D21/514, 349/5, 7, 8, 9, 58; 352/34, 242; 353/115, 353/119, 122**

(57) **CLAIM**

The ornamental design for a LCD video projector, as shown and described.

DESCRIPTION

FIG. 1 is a top perspective view of a LCD video projector of the present invention;

FIG. 2 is a front view thereof;

FIG. 3 is a top view thereof;

FIG. 4 is a first side view thereof;

FIG. 5 is an opposite side view of that shown in FIG. 4 thereof;

FIG. 6 is a bottom view thereof; and,

FIG. 7 is a rear view thereof.

1 Claim, 3 Drawing Sheets
